POLYMER COATED FABRIC

Francis E. Dreazy, Chicago, Ill., assignor to United States Rubber Company, New York, N.Y., a corporation of New Jersey

Application December 18, 1957, Serial No. 48,941

Term of patent 14 years

(Cl. D92—1)

Fig. 1 is a plan view of a polymer coated fabric showing my new design; and

Fig. 2 is an enlarged sectional view through the fabric of Fig. 1 along the line 2—2 of Fig. 1.

A complete design unit is included within the broken-line rectangle of Fig. 1, and this unit is reproduced in regular succession throughout the width and length of the fabric.

I claim:

The ornamental design for a polymer coated fabric, as shown.
